UNITED STATES PATENT OFFICE.

JOHN F. BURR, OF HOUSTON, MINNESOTA.

DESIGN FOR A HEAD FOR FENCING-HAMMERS.

51,773.

Specification for Design. Patented Feb. 12, 1918.

Application filed June 25, 1917. Serial No. 176,876. Term of patent 14 years.

To all whom it may concern:

Be it known that I, JOHN F. BURR, a citizen of the United States, residing at Houston, in the county of Houston and State of Minnesota, have invented a new, original, and ornamental Design for a Head for Fencing-Hammers, of which the following is a specification, reference being had to the accompanying drawing, forming a part thereof.

The figure is a perspective view of a head for fencing hammers, showing my new design.

I claim:

The ornamental design for a head for fencing hammers, as shown.

JOHN F. BURR.

Witnesses:

A. P. OMODT,
W. MERNILLA.
